US0D1087711S

(12) **United States Design Patent** (10) **Patent No.:** **US D1,087,711 S**
(45) **Date of Patent:** **** Aug. 12, 2025**

(54) **WALLET CARD**

(71) Applicant: **Alex Shlaferman**, Brooklyn, NY (US)

(72) Inventor: **Alex Shlaferman**, Brooklyn, NY (US)

(73) Assignee: **DYNAMITE MARKETING, INC.**,
New York, NY (US)

(**) Term: **15 Years**

(21) Appl. No.: **29/894,301**

(22) Filed: **Jun. 8, 2023**

(51) **LOC (15) Cl.** **08-05**

(52) **U.S. Cl.**

USPC **D8/105**; D8/16; D8/19

(58) **Field of Classification Search**

USPC D2/501, 502; D3/247, 249; D8/14, 16,

D8/19, 26, 29, 55, 82, 105
